DESIGN FOR A GEOMETRIC PUZZLE

Walter Koerschgen, Greenwich, Conn.

Application November 21, 1936, Serial No. 66,051

Term of patent 3½ years

To all whom it may concern:

Be it known that I, Walter Koerschgen, a citizen of the German Reich, and resident of Greenwich, Connecticut, have invented a new, original, and ornamental Design for a Geometric Puzzle, of which the following is a specification, reference being had to the accompanying drawing, forming part thereof.

The figure is a perspective view of the puzzle showing my new design.

I claim:

The ornamental design for a geometric puzzle, substantially as shown.

WALTER KOERSCHGEN.
